BUOYANCY CONTROL DEVICE

Merrill G. Leonard, Sharon, Pa., assignor to
Westinghouse Electric Corporation, East Pittsburgh,
Pa., a corporation of Pennsylvania

Application August 5, 1944, Serial No. 548,276

7 Claims. (Cl. 114—20)

1

My invention relates to torpedoes, and more particularly to an exercise head for a torpedo and the apparatus for discharging the ballast fluid from the exercise head. During the final run of the torpedo, it is, of course, provided with a war head and no special provision need be made for recovery of the torpedo, but since it is highly essential that each torpedo at least receive several practice or exercise, runs before actually being used in battle, it is important that the torpedo be provided with an exercise head, and that the torpedo be buoyant at the end of its run to facilitate its recovery.

The Government of the United States has been granted a certain royalty-free license for governmental purposes with respect to the invention herein described.

One object of my invention is the provision of means for readily removing the ballast fluid from an exercise head of a torpedo.

Another object of my invention is the provision of a system of control for effecting the removal of the ballast fluid from an exercise head of a torpedo at the proper time after firing of the torpedo.

Another object of my invention is the provision of electromagnetically operated valve means for controlling the flow of blow-off fluid from the flask containing the blow-off gas under high pressure.

A more specific object is the provision of a solenoid actuated hydrostatically unbalanced valve for maintaining the outlet from the high pressure gas flask closed and of means associated with said valve for effecting the operation of the valve at the right time for opening the outlet from the gas containing flask.

Other objects and advantages will become more apparent from a study of the following specification and the accompanying drawing, in which:

Figure 1 is a somewhat schematic showing of an exercise head of a torpedo and the starting gear for the torpedo;

Fig. 2 is a side view of my special valve for controlling the flow of blow-off fluid, with certain parts shown in section to more accurately illustrate the construction of the valve; and

Fig. 3 is an end view of my valve on line III—III in Fig. 2.

Referring to Fig. 1, 1 designates the firing tube of the torpedo which is shown provided with a dog 2 for actuating a trigger switch 3. This trigger switch 3 has its operating mechanism suitably sealed from the water outside of the torpedo and when operated upon firing of the

2

torpedo effects the closing of a circuit for starting the propulsion equipment of the torpedo. The propulsion equipment is not shown, since in itself it forms no part of this invention.

The exercise head 4 is connected to the left of the partition 5 and is provided with a suitable discharge valve 6 and an inlet 7 for admitting the gas, under high pressure in flask 8, into the practice head. The flask 8 is provided with a pressure reducing valve 9 which has a coupling 10 of steel or some other strong metal connected to it. This coupling provides for the support of a solenoid 11, the plunger or armature 12 to be actuated by the solenoid, the trip switch 13 and also a pipe fitting 14 for connection to the conduit 15 leading to the inlet 7.

For a better understanding of the novel construction and function of my valve in the system of control, a sequence of operation of the elements associated with the exercise head may be of value at this point. Before firing of the torpedo, the manually operable switch 51 is closed and the screw 52 is screwed toward the right as seen in Fig. 2, to close the contacts of the trip switch 13. This operation establishes a circuit from the positive terminal of the battery 17 through the contacts 53 of the switch 13, conductor 54, the pilot lights 55 and 56, conductor 57 manually operable switch 51 to the negative terminal of the battery.

Another circuit is established from the positive terminal of the battery 17 through the solenoid 11, conductor 58, contacts 31 and 32 of the controller operated by the motor 27 to the energized conductor 57. Connected in parallel with the contacts 31 is a torpedo speed responsive switch 59. This switch may be actuated by Pitot tubes or as shown by a suitable scoop which is actuated by the water flowing past the torpedo and thus is caused to maintain its contact members closed.

It is apparent that the instant the torpedo speed has dropped to some selected low speed, the scoop 60 which is spring-biased to a downward position will cause opening of the contact members of this switch 59. This switch is not described in detail herein, since per se it constitutes no part of this invention.

At the moment the torpedo is fired, the trigger switch 3 is operated closing its contacts 16, whereupon a circuit is established from the battery 17, which circuit may be traced from the positive terminal of the battery through the actuating solenoid or coil 18 of the starting switch 19, conductor 20, controller switch contacts 33, conductor 22, contacts 16 and conductor 23 back to

the negative terminal of the battery 17. The starting switch 19 has a time constant which may be an inductive time constant and may be designated by the low resistance short-circuit coil 24. This means that when coil 18 is de-energized, the contacts 25 do not open until a predetermined time after de-energization of coil 18.

Operation of starting switch 19 closes the contacts 25, whereupon the propulsion motor is energized and a circuit is also established from the positive terminal of the battery through contacts 25, conductor 26, contacts 34, controller operating motor 27 and conductor 28 to the negative terminal of the battery.

The controller operating motor 27 is of the constant speed type and operates the four contact members 31, 32, 33 and 34 in the order recited. Normally, these contacts are closed. The closed position of the contacts is, of course, maintained at the starting of the torpedo. Since the propulsion equipment, a short time after firing of the torpedo, takes hold, the torpedo is proceeding through the water and the speed responsive switch 59 actuated by the scoop 60, is in closed position. Therefore, the energization of the solenoid 11 no longer is established through both the contacts 31 and the contacts of the speed responsive switch 59 but is only established through the contacts of the speed responsive switch 59.

The motor 27 has its contacts so arranged that contact 31 opens as soon as the torpedo has obtained full speed in the water, that is, the time constant of contacts 31 is sufficient in length to permit the speed responsive relay or switch to assume control.

If, after the torpedo is in the water, there be a voltage failure, or the battery voltage, because of exhaustion or some other cause, drops, the solenoid 11 becomes de-energized and the valve 62 is thus opened. Similarly if the torpedo speed decreases below a given value the speed responsive relay opens the circuit for solenoid 11 and the valve 62 is caused to open. When valve 62 opens the fluid from flask 8 will be expelled from the flask through the steel pipe fitting 16, the conduit 15 and opening 7 into the exercise head.

From the foregoing it is clear that if the torpedo speed decreases to a given low value, the voltage fails or the end of the run is attained the solenoid 11 is de-energized.

Immediately after the contacts 32 open, contacts 33 open which de-energize the actuating coil 18 and the propulsion equipment is thereby stopped by the opening of contacts 25. Since starting switch 19 has a short time constant, contacts 25 will remain closed for a sufficient length of time to permit the motor 27 to operate contact 34 to interrupt the circuit for the motor 27. All the circuits are thus de-energized except the pilot lights.

For the details of the valve, reference should be had to Figs. 2 and 3. It will be noted that the plunger 12 has a somewhat smaller extension 61 which is screwed into the plunger 12. This extension has a rubber or nylon valve seat 62 for closing the opening leading to the reducing valve 9. The plunger 12 itself is made of soft iron or some other magnetic material to provide a considerable force towards the left to close the opening from the reducer valve when the solenoid 11 is energized. Since it would be impractical to maintain the current in solenoid 11 for a great length of time as, for instance, dur-

ing storage of the torpedo, the guide sleeve 63 for the solenoid is provided with a screw 52 for engaging the right-hand end of the plunger. This screw 52, when the torpedo is in storage, is screwed down against the plunger to hold the valve closed independent of any energization or de-energization of the solenoid 11. The pilot lights are provided for facilitating recovery of the torpedo and to guard against the possibility that a torpedo might be fired without releasing the valve controlling the blow-off fluid. I provide this trip switch 13 in the circuit for the pilot lights so that a mere inspection of the torpedo at the front will indicate whether or not the screw 52 has been turned back to release the valve, thus making the torpedo ready for firing.

While I have shown the motor 27 as connected to the battery through the contact 25, it is apparent that the contacts 31, 32, 33 and 34 need not necessarily be operated by a motor but may just as readily be operated from the driving shaft of the propulsion motor.

While I have shown one embodiment of my special electromagnetically operated valve and one system of control, it is readily apparent that others, particularly after having had the benefit of the teachings of my invention may devise other systems of control and other valves for accomplishing the same or similar purposes. I, therefore, do not wish to be limited to the particular showing made and description hereinbefore given, but wish to be limited only by the claims hereto appended.

I claim as my invention:

1. In a system of control for pneumatically expelling the ballast liquid from the practice head of a torpedo by means of a gas from a high pressure gas flask mounted on the practice head, in combination, a source of gas pressure comprising a flask, a conduit connecting the flask with the practice head, a valve for closing the conduit, an energized solenoid for holding the valve closed, and means responsive to either the stopping of the torpedo in its run or a predetermined run of the torpedo, whichever in point of time occurs first, for de-energizing the solenoid to thus open the conduit to cause gas under pressure to enter the practice head to expel the ballast liquid from the practice head.

2. In a system of control for pneumatically expelling the ballast liquid from the practice head of a torpedo, by means of a fluid under relatively high pressure from a high pressure flask, through suitable valve means in the practice head permitting the flow of the ballast liquid, when subjected to a predetermined pressure, from the practice head to thus make the torpedo buoyant, in combination, a conduit coupled to the flask; valve means comprising a valve seat in the conduit, a hydrostatically unbalanced valve disposed to seat on the valve seat, said valve being connected to one end of a plunger of magnetic material, a non-magnetic guide sleeve for the plunger, a solenoid disposed about the sleeve and plunger which solenoid when energized holds the valve on its seat against the pressure of the fluid in said conduit, and a second conduit providing a connection from the flask to the interior of the practice head when the valve is open, and means responsive either to a predetermined operation of the torpedo or to a predetermined speed of the torpedo, depending on whichever occurs first, for de-energizing said solenoid to effect the opening of said valve to thus admit fluid from the flask into

the practice head to displace the ballast liquid and thus make the torpedo buoyant.

3. In a system of control for pneumatically expelling the ballast liquid from the practice head of a torpedo, by means of a fluid under relatively high pressure from a high pressure flask, through suitable valve means in the practice head permitting the flow of the ballast liquid when subjected to a predetermined pressure, from the practice head to thus make the torpedo buoyant, in combination, a conduit coupled to the flask; valve means comprising a valve seat in the conduit, a hydrostatically unbalanced valve disposed to seat on the valve seat, said valve being connected to one end of a plunger of magnetic material, a nonmagnetic guide sleeve for the plunger, a solenoid disposed about the sleeve and plunger which solenoid when energized holds the valve on its seat against the pressure of the fluid in said conduit, and a second conduit providing a connection from the flask to the interior of the practice head when the valve is open, signal lights, an adjustable stop disposed at the other end of the plunger, which stop when adjusted to one extreme position operates the plunger to firmly seat the valve, and when adjusted to its other extreme position effects the operation of the signal lights to indicate that the solenoid is energized to hold the valve closed, means responsive to a selected speed of the torpedo in the water for de-energizing said solenoid to open the valve to thus admit fluid from the flask into the practice head displacing the ballast liquid to make the torpedo buoyant.

4. In a system of control for pneumatically expelling the ballast liquid from the practice head of a torpedo, by means of a fluid under relatively high pressure from a high pressure flask, through suitable valve means in the practice head permitting the flow of the ballast liquid, when subjected to a predetermined pressure, from the practice head to thus make the torpedo buoyant, in combination, a conduit coupled to the flask; valve means comprising a valve seat in the conduit, a hydrostatically unbalanced valve disposed to seat on the valve seat, said valve being connected to one end of a plunger of magnetic material, a nonmagnetic guide sleeve for the plunger, a solenoid disposed about the sleeve and plunger which solenoid when energized holds the valve on its seat against the pressure of the fluid in said conduit, and a second conduit providing a connection from the flask to the interior of the practice head when the valve is open, means responsive to a predetermined operation of the torpedo, after being fired, for effecting the de-energization of said solenoid to open the valve to thus admit fluid from the flask into the practice head displacing the ballast liquid to make the torpedo buoyant.

5. In a system of control for pneumatically expelling the ballast liquid from the practice head of a torpedo, by means of a fluid under relatively high pressure from a high pressure flask, through suitable valve means in the practice head permitting the flow of the ballast liquid, when subjected to a predetermined pressure, from the practice head to thus make the torpedo buoyant, in combination, a conduit coupled to the flask; valve means comprising a valve seat in the conduit, a hydrostatically unbalanced valve disposed to seat on the valve seat, said valve being connected to one end of a plunger of magnetic ma-

terial, a nonmagnetic guide sleeve for the plunger, a solenoid disposed about the sleeve and plunger which solenoid when energized holds the valve on its seat against the pressure of the fluid in said conduit, and a second conduit providing a connection from the flask to the interior of the practice head when the valve is open, signal lights, an adjustable stop disposed at the other end of the plunger, which stop when adjusted to one extreme position operates the plunger to firmly seat the valve, and when adjusted to its other extreme position effects the operation of the signal lights to indicate that the solenoid is energized to hold the valve closed, means responsive to a selected speed of the torpedo in the water for de-energizing said solenoid to open the valve to thus admit fluid from the flask into the practice head displacing the ballast liquid to make the torpedo buoyant.

20 6. In a system of control for pneumatically expelling the ballast liquid from the practice head of a torpedo, by means of a fluid under relatively high pressure from a high pressure flask, through suitable valve means in the practice head permitting the flow of the ballast liquid, when subjected to a predetermined pressure, from the practice head to thus make the torpedo buoyant, in combination, a conduit coupled to the flask; valve means comprising a valve seat on the conduit, a hydrostatically unbalanced valve disposed to seat on the valve seat, said valve being connected to one end of a plunger of magnetic material, a nonmagnetic guide sleeve for the plunger, a solenoid disposed about the sleeve and plunger which solenoid when energized holds the valve on its seat against the pressure of the fluid in said conduit, and a second conduit providing a connection from the flask to the interior of the practice head when the valve is open, means responsive to a predetermined operation of the torpedo, after being fired for effecting the de-energization of said solenoid to open the valve to thus admit fluid from the flask into the practice head displacing the ballast liquid to make the torpedo buoyant, means responsive to a selected speed of the torpedo in the water for also effecting the de-energization of said solenoid to similarly make the torpedo buoyant, and means for selecting the operation of either of said last two means depending on whichever of the respective control effects for said last two means occurs first.

7. In a system of control for pneumatically expelling the ballast liquid from the practice head of a torpedo, by means of a fluid under relatively high pressure from a high pressure flask, through suitable valve means in the practice head permitting the flow of the ballast liquid, when subjected to a predetermined pressure, from the practice head to thus make the torpedo buoyant, in combination, a conduit coupled to the flask; valve means comprising a valve seat in the conduit, a hydrostatically unbalanced valve disposed to seat on the valve seat, said valve being connected to one end of a plunger of magnetic material, a nonmagnetic guide sleeve for the plunger, a solenoid disposed about the sleeve and plunger which solenoid when energized holds the valve on its seat against the pressure of the fluid in said conduit, and a second conduit providing a connection from the flask to the interior of the practice head when the valve is open, signal lights, an adjustable stop disposed at the other end of the plunger, which stop when adjusted to one extreme position operates the plunger to firmly

seat the valve, and when adjusted to its other extreme position effects the operation of the signal lights to indicate that the solenoid is energized to hold the valve closed, means responsive to a predetermined operation of the torpedo, after being fired, for effecting the de-energization of said solenoid to open the valve to thus admit fluid from the flask into the practice head displacing the ballast liquid to make the torpedo

buoyant, means responsive to a selected speed of the torpedo in the water, for also effecting the de-energization of said solenoid to similarly make the torpedo buoyant, and means for selecting the operation of either of said last two means depending on whichever of the respective control effects for said last two means occurs first.

MERRILL G. LEONARD.
